CLOSURE ASSEMBLY DEVICE

Guy McLaughlin, Jr., Lancaster, Pa., assignor to Armstrong Cork Company, Lancaster, Pa., a corporation of Pennsylvania

Application August 23, 1952, Serial No. 306,010

3 Claims. (Cl. 144—2)

This invention relates to a device for paraffining and turning wood top stoppers, i. e., bottle closures having a top of wood with a recess therein which receives a cork stopper which is adhesively secured to the top within the recess. More particularly, the invention relates to a device which simultaneously applies paraffin to the tip of the cork and turns a cork stopper 360 degrees with respect to the wood top immediately after glue has been applied to the wood top, serving to properly and evenly distribute the glue to insure a more positive adhesive bond between the wood top and the cork stopper.

In the manufacture of wood top cork stoppers such as those conventionally used in the sealing of liquor containers, etc., it has been found desirable to rotate the cork stopper through 360 degrees in order to insure proper distribution of the adhesive between the cork and the wood top. It has been found that if the cork stopper is rotated 360 degrees with respect to the wood top after the glue has been applied and before the glue has set, the wiping action tends to uniformly distribute the glue in the area between the wood top and the cork stopper, giving a more complete bond and at the same time resulting in a neat appearance, inasmuch as the glue line will be a very thin line at the zone of juncture between the cork and the wood. Prior to the invention set forth in this application, this operation of turning the cork stopper with respect to the wood top was done by hand and required a great deal of expense in labor cost.

In the manufacture of wood top stoppers of the type disclosed herein, it is necessary to coat the tip of the cork with paraffin or other protective coating to prevent the contents of the bottle from deleteriously affecting the cork, and also to prevent the cork from imparting a taste to the contents of the bottle. By using the machine described herein, it is possible to perform the paraffining operation and simultaneously therewith rotate the cork through 360 degrees with respect to the wood top to properly distribute the glue between the cork and the wood top. The machine can also be used to perform these operations separately. For example, it can be used to turn corks which do not require paraffin or it may be used to paraffin corks which are not secured to wood tops.

An object of this invention is to provide a machine which will apply fluid paraffin to the tip of cork stoppers.

Another object of this invention is to provide a mechanism which will rotate the cork with respect to the wood top at the time the paraffin is being applied to the tip of the cork to insure even and uniform distribution of the adhesive between the cork and the wood top, or to perform either of these operations alone.

Other obvious objects and advantages of this device will be apparent from consideration of the attached drawings, in which:

Figure 1 is a side elevational view of the machine; Figure 2 is a front elevational view of the device; and Figure 3 is a view of the cylinder cam which operates the paraffin-applying and cork-feeding device.

Referring to the drawing, there is shown a conveyor

band 2 which carries wood top cork stoppers 3 in a continuous manner immediately after the cork has been put in place in the wood top with a film of fluid glue between the cork and the wood top. The conveyor band 2 supplies the cork and wood top assemblies 3 to a rotary turntable 4 having suitable pockets 4' in its periphery to receive the wood top stopper assemblies 3 which are fed into engagement therewith from the conveyor 2. The turntable 4 is intermittently rotated to carry the assemblies 10 from the position at which they are received from the conveyor band 2 through an arc of 90 degrees to bring the cork stopper in proper alignment with a rotatable paraffining head 5.

The entire device is driven by a motor, not shown, 15 connected to a sprocket 6 which by means of chain 7 drives a sprocket 8 keyed to a shaft 9. Also keyed to shaft 9 is the cylindrical cam 10. The cam track 11 of the cylindrical cam 10 engages cam followers 12 on the rotatable plate 13. The cam track 11 is of such contour 20 that one rotation of the cam will move the plate 13 an amount equal to the distance from the center of one of the cam followers 12 to the center of the next cam follower 12. The number of cam followers 12 on plate 13 corresponds to the number of stopper-receiving recesses in 25 the turntable 4, and the spacing of the cam followers 12 is the same as the spacing of the pockets in the turntable 4. The turntable 4 and the cam plate 13 are both keyed to a common shaft 14. The height of the turntable 4 on shaft 14 is adjustable by means of clamping screw 15 passing 30 through groove 16 in the shaft 14. This makes it possible for the turntable 4 to accommodate wood tops of different thicknesses. It will be clear from this description that one revolution of the cylindrical cam 10 on the shaft 9 will 35 rotate the turntable 4 a distance equal to the distance from the center of one of the stopper-receiving recesses to the center of the next stopper-receiving recess.

Also positioned for engagement with the cam track 11 of cylindrical cam 10 is a second cam plate 17 carrying a plurality of cam followers 18. These cam followers 18 40 are the same as cam followers 12 and are engaged by the same cam track 11 of cylindrical cam 10. Each rotation of the cylindrical cam 10 will move the cam plate 17 a distance equal to the distance from the center of one cam follower 18 to the center of the next cam follower 18. 45 This arrangement transmits intermittent rotary motion to the cam plate 17 the same as to the cam plate 13; however, it should be borne in mind that the contour of the cam track 11 is such that during a cycle of rotation of the cylindrical cam 10, only one of the plates 13 or 17 will 50 be in motion at any one time. In other words, while cam plate 13 is being moved, cam plate 17 will be stationary, and vice versa.

The outer periphery of cam plate 17 carries a gear 19 55 which engages other gears in a gear train and through gear 20 engages a gear 21 which is keyed to shaft 22 on which paraffining head 5 is mounted. It will be seen from this arrangement that the intermittent rotary motion imparted from the cylindrical cam 10 to the cam plate 17 60 imparts intermittent rotary motion to the paraffining head 5. The gear train between the gear 19 and the gear 20 is of such ratio that rotation of the cam plate 17 from the center of one cam follower 18 to the center of the next cam follower 18 will rotate the gear 21 on the shaft 22 one complete revolution, or 360 degrees. The paraffining head 5 is mounted on hollow shaft 22 through which molten paraffin is fed. The paraffin may be maintained 65 in molten condition within this tube by suitable heaters, not shown.

In order for the cork stopper 3 to be placed in position under the paraffining head 5, it is necessary that the paraffining head be adapted for reciprocating motion in a vertical direction as well as rotary motion. This is

accomplished by a collar 23 adjustably mounted on the head 5. This collar 23 is engaged by cam rollers 24 mounted on rocker arms 25 which pivot about a pivot point 26. The other end of rocker arm 25 carries a cam follower 27 for engagement with a cam 28 keyed to the shaft 9. The positioning of the cam 28 on the shaft 9 is such that it will depress the cam follower 27 immediately after the paraffining head 5 has completed its rotating cycle. This depressing of the cam follower 27 will pivot the rocker arm 25 about pivot point 26 and raise the paraffining head 5. A spring 29 is attached to the end of the rocker arm 25 and the frame of the machine so that the spring will return the paraffining head 5 to its lowermost position when the cam follower 27 has moved off the high point of the cam 28. The vertical position of the paraffining head may be adjusted by turning the locking nuts 30 on the threads 31 on the shaft 22. This raises or lowers the collar 23 on the shaft 22. This adjustment is provided to accommodate corks of different heights. While the paraffining head 5 is moved upwardly, the cylindrical cam 10 imparts intermittent rotary motion to the turntable 4 and moves the completed stopper from its position beneath the paraffining head 5 and brings the next stopper into position under the paraffining head. As soon as this operation has been accomplished, the cylindrical cam 10 imparts rotary motion to the cam plate 17, which in turn rotates the paraffining head 5.

The paraffining head is preferably provided with a pad of felt or other absorptive material in its lower extremity, as shown at 32, and the frictional drag between this felt pad and the cork at the time this paraffin is being applied is sufficient to rotate the cork. The size and shape of the felt pad may be changed, depending on the size of the cork being coated and the area to be coated. In some instances, only the tip of the cork is coated; while in other instances, the tip and a portion of the side are coated. The paraffining head 5 rotates the cork with respect to the wood while the wood top is held by a spring 33, secured to the frame of the machine. It will be understood also that the liquid glue acts as a lubricant between the cork and wood top and permits easy rotation of one with respect to the other.

Inasmuch as there is a tendency for the cork to adhere to the paraffin-applying pad, it is necessary to provide means to prevent the cork from following the pad when the paraffining head is moved in an upward direction. This is accomplished by tongs 34, the arms of which are pivoted at pivot point 35. The arms of the tongs 34 are provided with meshing gears 36 so that when the one arm moves, the other will move a proportionate distance. The one arm 34 is keyed to a shaft 37, and a link 38 is also keyed to shaft 37. This link 38 is connected by means of another link 39 to a rocker arm 40 which pivots about pivot point 41. The rocker arm 40 has a cam follower 42 which engages another cam 43 mounted on the common shaft 9. The contour of the cam 43 and its position on the shaft 9 is such that it will depress the end of rocker arm 40 immediately after rotary motion has ceased in the paraffining head 5. The downward motion on the rocker arm 40 will close the tongs 34 and the fingers 44 will engage the cork 3 and hold it while the paraffining head 5 is withdrawn. Immediately after the bond between the paraffining head and the cork is broken, the tongs open by means of spring 45, one end of which is attached to the end of the arm 40 and the other end of which is attached to the frame of the machine. This releases the cork and it is free to move from its position under the paraffining head to the next station, and another cork is brought into position under the paraffining head.

As the corks move around the machine, when they reach a point 90 degrees from the point at which the paraffining is accomplished, or 180 degrees from the point at which they were fed into the turntable 4, they are fed

onto the same conveyor 2 and carried away from the machine.

In the operation of this device, the corks 3 and wood tops, which have been previously assembled with a film of liquid adhesive disposed therebetween, are fed on the conveyor 2 to suitable wood top receiving recesses in the intermittently rotating turntable 4. The wood top with the cork positioned therein is moved by the turntable 4 through an arc of 90 degrees and comes to rest directly under a paraffining head 5. The paraffining head is then lowered so that the felt pad 32 positioned at the lower extremity of the paraffining head engages the tip of the cork and applies a film of paraffin thereto. While the felt pad is in engagement with the cork, the entire paraffining attachment is rotated through 360 degrees and the friction between the felt pad and the cork is sufficiently great that the cork will rotate with the paraffining head while the wood top is held from rotation by the spring 33.

After the paraffin has been applied and the cork has been rotated, the paraffining head 5 moves upwardly and the intermittently rotating turntable 4 moves the cork and wood top assembly 3 away from its position beneath the paraffining head through an arc of 90 degrees to a point where the cork and wood top assembly is placed on the same conveyor which fed it to the device at a diametrically opposite point.

During the operating cycle of the device, all the motions are effected by a plurality of cams mounted for rotation on a common shaft 9. The cylindrical cam 10 is provided with a cam track 11 for engagement with one set of cam followers 12 mounted on plate 13 and a second set of cam follower 18 mounted on plate 17. One complete revolution of the cylindrical cam 10 moves the plates 13 and 17 a distance equal to the distance from the center of one cam follower to the center of the next cam follower. The contour of the cam track 11 is such that when the cam plate 13 is being moved, the cam plate 17 is stationary, and vice versa. The plate 13 and the turntable 4 are both keyed to a common vertical shaft 14 so that the intermittent rotary motion imparted to the plate 13 by the cylindrical cam 10 through cam follower 12 will be transmitted through the shaft 14 to the turntable 4. The number and position of the wood top receiving recesses in the turntable 4 correspond to the number and position of cam followers 12.

The plate 17 is provided on its outer periphery with a gear 19 which, through a suitable gear train, is in mesh with gear 21 keyed to the paraffining head. Gear 21 is of sufficient width that it will mesh with gear 20 regardless of whether the paraffining head 5 is in its lowermost position or in its uppermost position. The gear train between gear 19 and gear 21 is of such ratio that the motion imparted to the cam plate 17 during one revolution of the cylindrical cam 10 will turn the paraffining head 5 through one complete revolution.

The vertical reciprocating motion is imparted to the paraffining head 5 by a cam 28 keyed to shaft 9. This cam 28 actuates rocker arm 25, the end of which is in engagement with the collar 23 by means of the roller 24. The positioning of the cam 28 on the shaft 9 is such that the high point of the cam will depress the end of rocker arm 25 immediately after cylindrical cam 10 has finished moving plate 17 the distance from the center of one cam follower 18 to the center of the next cam follower 18. This prevents the raising of the paraffining head before it has completed one full revolution in contact with the cork. The cam 28 is so contoured that it will permit the spring 29 to pull the head down into engagement with the cork immediately before the cylindrical cam 10 starts to rotate the paraffining head 5.

Immediately before the cam 28 lifts the paraffining head from its contact with the cork, the tongs 34 close and the fingers 44 engage the cork to prevent the cork from following the paraffining head as it moves upwardly. These tongs 34 are actuated by cam 43 keyed to shaft 9.

The positioning of cam 43 is such that it will depress rocker arm 40 immediately before the paraffining head 5 starts its upward travel but after the paraffining head 5 has completed its cycle of rotation. The tongs 34 are closed for a very short period of time, after which the spring 45 raises the rocker arm after the roller 42 moves off the high point of the cam 43. This action of the spring 45 opens the tongs. Immediately after the tongs have opened, the cylindrical cam 10 engages one of the cam followers 12 on plate 13, rotating the same and moving the completed stopper from its position under the paraffining head and moving another stopper into position for the next cycle of the device.

It will be noted that with this arrangement of cams all properly mounted on one shaft, synchronization of the moving parts can be easily achieved and maintained during continuous high-speed operation.

I claim:

1. In a device for coating corks yieldably held to tops by unset adhesive, a rotatable pocketed carrier for moving equally spaced tops with corks thereon from a feeding device through a coating station to a delivery position, a feeding device for delivering tops with corks to the carrier, coating means at the coating station mounted for rotation and reciprocation about and along an axis normal to the carrier and substantially coincident with the axis of a cork in coating position at the coating station, means for rotating the carrier and coating means alternatively, and means for reciprocating the coating means into and out of engagement with the cork, said device being characterized by the rotating means rotating the carrier the space between pockets alternatively with rotating the coating means one revolution and reciprocating the coating means one cycle.

2. In a device for coating corks yieldably held to tops by unset adhesive, a rotatable pocketed carrier for moving equally spaced tops with corks thereon from a feeding device through a coating station to a delivery position, a feeding device for delivering tops with corks to the

carrier, coating means at the coating station mounted for rotation and reciprocation about and along an axis normal to the carrier and substantially coincident with the axis of a cork in coating position at the coating station, means for rotating the carrier and the coating means alternatively and means for reciprocating the coating means into and out of engagement with the cork, and means provided at the coating station to engage the top to insure relative rotation between the cork and top, said device being characterized by the rotating means rotating the carrier in the space between pockets alternatively with rotating the coating means one revolution and reciprocating the coating means one cycle.

3. In a device for coating corks yieldably held to tops by unset adhesive, a rotatable pocketed carrier for moving equally spaced tops with corks thereon from a feeding device through a coating station to a delivery position, a feeding device for delivering tops with corks to the carrier, coating means at the coating station mounted for rotation and reciprocation about and along an axis normal to the carrier and substantially coincident with the axis of a cork in coating position at the coating station, means for rotating the carrier and the coating means alternatively and means for reciprocating the coating means into and out of engagement with the cork, and means for holding said cork while the coating means is moving out of engagement with the cork, said device being characterized by the rotating means rotating the carrier the space between pockets alternatively with rotating the coating means one revolution and reciprocating the coating means one cycle.
